UNITED STATES PATENT OFFICE.

CHARLES SOMERVILLE NELSON AND WILLIAM NEWBY COLAM, OF LONDON, COUNTY OF MIDDLESEX, ENGLAND.

DISPLAYING ADVERTISEMENTS ON CARS.

SPECIFICATION forming part of Letters Patent No. 364,279, dated June 7, 1887.

Application filed January 28, 1887. Serial No. 225,762 (No model.) Patented in England March 22, 1886, No. 3,997.

To all whom it may concern:

Be it known that we, CHARLES SOMERVILLE NELSON and WILLIAM NEWBY COLAM, subjects of the Queen of Great Britain, residing in

5 London, in the county of Middlesex, England, have invented certain new and useful Improvements in Displaying Advertisements on Tram-Cars and Similar Vehicles, (for which we have obtained a patent in Great Britain, No. 3,997, 10 bearing date March 22, 1886,) of which the following is a specification.

Our invention relates to a device for displaying advertisements on tram-cars, omnibuses, and similar vehicles; and the objects of 15 our invention are, first, to render the advertisements more attractive; second, to increase the area available for advertising purposes, and, therefore, thirdly, to increase the value of these vehicles as advertising mediums. We 20 attain these objects by mechanism illustrated in the accompanying drawings, in which—

Figure 1, Sheet No. 1, is a longitudinal section, and Fig. 2, Sheet No. 1, is a transverse section, of a tram-car, showing the general arrangement of the mechanism. Fig. 3, Sheet No. 2, is a sectional view, on an enlarged scale, showing the end of one of the advertising-rollers and one of the bearings supporting it. Fig. 4, Sheet No. 2, is a sectional view, on an 25 enlarged scale, showing the mechanism for operating the rollers. Fig. 5, Sheet No. 2, is a transverse section of a roller having six sides. Figs. 6, 7, 8, and 9, Sheet No. 3, are views, on an enlarged scale, showing the 30 mechanism for transmitting the motion necessary to operate the rollers from one of the axles of a car.

Similar letters refer to similar parts throughout the several views.

40 The rollers A A, &c., which are made with four or more sides to receive the advertisements, are mounted on a continuous axle, B, on each side of the vehicle, the rollers being in short lengths to coincide with the panels of 45 the car. The axles B B are mounted in suitable bearings, C C, &c., fixed to the frame of the vehicle. The rollers are inclosed in cases D D, formed across the angles formed by the junctions of the sides and roof of the car 50 or vehicle, suitable openings being provided

to allow one of the faces of each roller to be visible at one and the same time. Each axle carrying the advertising-rollers is caused to rotate by the following mechanism:

On one end of each of the axles B B we fix 55 a ratchet-wheel, b, and in convenient proximity thereto we mount loosely on the axle an arm, b', carrying a pawl, b'', engaging with the teeth of the ratchet-wheel b, a spring, b'', being provided to keep it engaged therewith. Connected with the arm b' is a cord or chain, b', which receives an intermittent reciprocating motion from mechanism to be hereinafter described, the cord or chain being carried down to the floor of the car by suitable guides. 60

When the cord or chain b' is pulled down, the pawl b'' on the arm b' rides over the teeth of the ratchet-wheel b, and as it is pulled up again by the spring b'' the pawl engages with the teeth of the ratchet-wheel b and moves the 65 axle sufficiently to bring the next side or face of the rollers opposite to the openings d d, &c., in cases D D, &c., which inclose them. It may sometimes be more convenient to effect the rotation of the axle carrying the advertising-rollers by the downward pull of the cord or chain instead of by the converse movement hereinbefore described, in which case the pawl and ratchet-wheel are arranged accordingly. 70

We do not bind ourselves to the use of rollers having four sides, as shown by Figs. 1, 2, 3, and 4, as rollers with six, eight, or more sides may be used. A roller with six sides is illustrated by Fig. 4. It will be obvious that the number of flat sides b', &c., cut or formed 75 on the boss of the ratchet-wheel b must coincide with the number of sides on the rollers A A, &c. The arms b' b', through the cords or chains b' b', receive their intermittent reciprocating motion through the following mechanism: Under one of the seats of the car is mounted, in suitable bearings, E E, a lay-axle, F, which carries a large pulley, G, the periphery of which is in frictional contact with one of the axles X of the car, or with a small pulley 80 fixed thereto. By this arrangement a considerable reduction of speed is obtained. To attain sufficient driving contact, the bearings E E are mounted in horn-plates E' E', so that the whole weight of the pulley G bears on the 85 90 95 100

axle X, and, if necessary, the periphery of the pulley, or that part of the axle with which it is in contact, may be covered with leather, rubber, or analogous material.

5 On the axle F is fixed a pulley, H, connected with a similar pulley, J, carried by an axle, K, mounted in bearings $k^1 k^2$, so that the ends of the axle are as nearly under the cords or chains $b^1 b^4$ as possible.

10 On each end of the axle K is fixed or formed a projecting arm, k' , with a small roller, k^2 , mounted on a pin at its free end. In suitable brackets, L L, either forming part of the bearing-brackets for the axle K or mounted independently on the under frame of the car, are pivoted levers l l. The ends of these levers on one side of their fulcrums are connected to the cords or chains $b^1 b^4$, and their opposite ends engage with the rollers $k^2 k^2$, carried on the ends of the arms $k^1 k^2$, thus imparting an intermittent reciprocating motion to the arms b^1 through the cords or chains $b^1 b^4$, the springs $b^3 b^5$ insuring the contact between the levers and the rollers.

15 It will be understood that the gear hereinbefore described is equally effective for operating the advertising-rollers whichever way the car is traveling, and permits of the axles carrying the rollers being geared down to almost any extent. In practice we find that thirty seconds is a convenient period for each side of the rollers to remain stationary and exposed to view, though it will be obvious that this period may be lengthened or shortened by varying the proportions of the motion-wheels.

20 We are aware that endless revolving or traveling bands or aprons have already been used on tram-cars and similar vehicles for displaying advertisements, and we are also aware that revolving rollers have been used on advertising-machines and other vehicles used solely for the purpose of advertising. We therefore do not claim the use of revolving rollers, broadly; but,

25 Having now particularly described and ascertained the nature of our said invention and in what manner the same is to be performed, we declare that what we claim is—

30 1. In a tram-car or other similar vehicle for the conveyance of passengers, the combination, with the car-body, of the polysided rollers journaled in the angle formed by the car roof and side, and the casing-strips having an

opening between them, to allow but one side of each roller to be visible at one and the same time, substantially as set forth.

35 2. In a tram-car or other similar vehicle for the conveyance of passengers, the combination, with the body of the vehicle, of the longitudinally-mounted polysided rollers journaled in the angle formed by the car roof and side, the casing-strips having an opening between them, so that only one side of each roller is visible to the occupants of the car at the same instant, and the mechanism for imparting an intermittent rotating motion to the rollers from the continuous rotating motion of one of the axles of the car, all arranged and operating in the manner hereinbefore set forth.

40 3. The combination of the polysided advertising-rollers, the ratchet-wheel secured on the roller-spindle, the arm provided with a pawl for turning the ratchet, a spring for turning the arm in one direction, a cord secured to the arm for turning it in the reverse direction, a rocking lever pivoted to the car-frame and secured to the cord, the projecting arm k' , having roller k^2 , for operating said lever and secured upon axle K, the friction-wheel journaled in sliding plates and bearing on the car-axle, and a driving-cord connecting the axle K with the said friction-wheel, substantially as and for the purpose set forth.

45 4. The combination of the car-frame mounted upon revoluble axles, a friction-wheel journaled in sliding plates and bearing upon one of the said axles, the projecting arm k' , having roller k^2 and secured upon the revoluble axle K, intermediate mechanism connecting the axle K with the said friction-wheel, the 50 rocking lever l, operated by the said roller, the advertising-rollers provided with a ratchet mechanism for turning them, and a cord connecting the said ratchet mechanism with the rocking lever, substantially as and for the purpose set forth.

55 In witness whereof we have hereunto signed our names in the presence of two subscribing witnesses.

CHARLES SOMERVILLE NELSON.
WILLIAM NEWBY COLAM.
